UNITED STATES PATENT OFFICE.

DOUGLAS M. B. H. COCHRANE, OF LONDON, ENGLAND.

CYCLE-SADDLE.

SPECIFICATION forming part of Letters Patent No. 610,429, dated September 6, 1898.

Application filed November 29, 1897. Serial No. 660,131. (No model.)

To all whom it may concern:

Be it known that I, DOUGLAS MACKINNON BAILLIE HAMILTON COCHRANE, Earl of Dun-
donald, a citizen of Scotland, residing at 34
5 Portman Square, in the city of London, Eng-
land, have invented a new and useful Yield-
ing Seat Applicable as a Saddle for Veloci-
pedes, of which the following is a specification.

My invention relates to the construction of
10 a yielding seat which may be used instead of a
saddle for a bicycle or other velocipedes.

Figure 1 of the accompanying drawings is
a front elevation. Fig. 2 is an end view of a
15 seat according to my invention. Fig. 3 is a
longitudinal section. Fig. 4 is an end view,
and Fig. 5 is a plan showing another modifi-
cation.

Referring first to Figs. 1 and 2, from flanges
A B of a frame which may be secured on a
20 saddle-support by a clamp C project obliquely
rods D and a pair of horizontal rods E, hav-
ing their ends attached to ring-frames F G,
approximately semicircular. From the flange
25 A there also projects horizontally a screwed
rod H, having fitted on it free to slide a disk
I, outside of which is a fly-nut J. A number
of straps K, of leather, strong fabric, or the
like, are fixed at one end to the ring G. Their
30 other ends are strained over the other ring F
and are attached by buckles to the disk I.
Each of the straps K can be independently
strained more or less by its buckle, and all
35 of these can be strained simultaneously by
screwing up the nut J. The straps K consti-
tute a yielding seat, some of the straps of
which may be made to yield more or less to
suit the persons seated on them.

As shown in Figs. 3, 4, and 5, the frames P
have approximately semicircular rims con-
40 nected by ribs to sleeves Q, which are fitted
to slide on squared parts of a bolt R, having
parts of it screw-threaded and fitted with
nuts S and having its middle secured by a
clamp C to the saddle-support. The straps
45 K, which form the seat, are secured by stitch-
ing or otherwise to the rims of the frames P
and can be more or less stretched by screw-
ing outward the nuts S. When it is desir-
able that each of the straps K should be ca-
50 pable of being separately tightened, it may
have its end secured by a buckle to the rim
of frame P. The straps K may be attached to a

cross-band N to prevent them from spreading
apart at the middle. Instead of employing
separate straps K a single piece of canvas or
55 other fabric may be used; but separate straps
are preferable, as they can be so strained as to
allow local yielding where required. A cush-
ion may also be placed on the straps or fabric.

Having thus described the nature of this
invention and the best means I know for car-
rying the same into practical effect, I claim—

1. A yielding seat for bicycles comprising
semicircular ring-frames having a number of
straps strained over them, a screw-threaded
65 rod mounted on a seat-support, a sleeve slid-
ing on said rod and operatively connected
with the ends of said straps, and a nut on said
rod engaging said sleeve whereby to adjust
simultaneously the tension of all of the straps,
70 substantially as described.

2. A yielding seat for bicycles comprising
a supporting-rod having on opposite sides of
its center a screw-threaded portion, sleeves
75 slidably supported on either end of said rod
and having extending upward therefrom ribs
or bars supporting ring-frames, a series of
straps strained over said ring-frames, and
nuts engaging the screw-threads of said rod
and bearing against said sleeves, whereby to
80 adjust simultaneously the tension of all of the
straps, substantially as described.

3. A yielding seat for bicycles comprising
a supporting-rod having on opposite sides of
its center a screw-threaded portion and be-
85 yond said screw-threads having squared ends,
sleeves slidably supported on said squared
portions and having cylindrical projections
encircling said threads, ribs or bars extending
upward from said sleeves and supporting
90 ring-frames, a series of straps strained over
said ring-frames, and nuts engaging the
screw-threads of said rod and bearing against
said sleeves, whereby to adjust simultane-
ously the tension of all of the straps, substan-
95 tially as described.

In testimony whereof I have signed my
name to this specification, in the presence of
two subscribing witnesses, this 16th day of
November, A. D. 1897.

DOUGLAS M. B. H. COCHRANE.
